(57) **CLAIM**

The ornamental design for a hair dryer as shown and described.

DESCRIPTION

FIG. 1 is a front view of a hair dryer according to the claimed design.

FIG. 2 is a rear view of the hair dryer.

FIG. 3 is a left side view of the hair dryer.

FIG. 4 is a right side view of the hair dryer.

FIG. 5 is a plan view of the hair dryer.

FIG. 6 is a bottom view of the hair dryer; and,

FIG. 7 is a perspective view of the hair dryer.

The broken lines in FIG. 2 depicting a portion of the hair dryer are for illustrative purposes only and form no part of the claimed design.
